UNITED STATES PATENT OFFICE.

GARTH G. GILPIN, OF RIVERSIDE, ILLINOIS, ASSIGNOR TO UNION METAL PRODUCTS COMPANY, OF CHICAGO, ILLINOIS, A CORPORATION OF DELAWARE.

DIAPHRAGM BUFFER MECHANISM.

Application filed April 2, 1926. Serial No. 99,326.

Upper buffer springs are used to keep the diaphragm face plates of adjacent passenger train cars in contact with each other on either a straight or curved track. Semi-elliptical or bowed springs are used for this purpose because they can also be arranged to keep the face plate in the center of the car and also maintain the face plate in its proper angular position. These semi-elliptical springs are attached to the diaphragm face plate at their middle portion and have their extremities attached to the car in such a way as to obtain the above mentioned desired results.

A semi-elliptical spring can be positioned and attached on the outside of the car so that it is noiseless; easy to inspect; accessible for repairs and has a low maintenance cost.

It is common practice to attach the middle of a semi-elliptical spring to a diaphragm face plate and attach its extremities to the end wall of the car by means which permit the ends of the spring to move and also provide an engagement between one extremity of the spring and the means that becomes effective when the face plate is forced into an oblique position with respect to the car, in rounding curves, or when it is caused to chafe by the uneven running of the car, which engagement distorts the spring, thereby tending to return the face plate to normal position. A sliding arrangement or a shackle construction may be used for this purpose.

My invention relates to cars equipped with diaphragm face plates and has for its object the particular and peculiar manner of positioning a pair of quarter elliptic springs between the face plate and the car, each of which springs has one end rigidly secured to one of the aforesaid elements and means for attaching the opposite ends of the springs to the other of the aforesaid elements, which means permit the ends of the spring to move a predetermined amount to accomplish the desired results mentioned heretofore.

Some railway messenger train cars recently constructed are provided with an apiced diaphragm which acts as a water shed and also prevents the accumulation of cinders, etc. Such apiced diaphragms require an apiced diaphragm face plate and as the spring must be attached to the face plate outside of the diaphragm the middle

portion of the spring is considerably higher from the rail than when applied to a face plate of the old construction. It is not customary nor practical in such cars to raise the end carline or ramp of the end wall of the car. When a straight semi-elliptical spring is used with an apiced face plate its extremities do not bear upon the end carline, thus necessitating building up an expensive and cumbersome bracket which must be very strong to accommodate the spring.

It would be very difficult to form a semi-elliptic spring with its ends out of alignment with the middle portion, as would be required to meet the conditions as illustrated in Figs. 4 and 5. In order to properly function the leaves of an elliptic spring must be in contact over their entire area which condition is difficult to obtain when a compound leaf spring is arched in two planes normal to each other.

My invention is especially adaptable to cars equipped with apex diaphragms and apiced face plates and has for its further object the particular positioning of a pair of quarter-elliptic springs between the face plate and the car. The springs have their longitudinal axes at an angle to each other. The ends of the springs adjacent the middle of the car are located above the diaphragm while their opposite ends are located over the end carline which necessitates the ends of the spring adjacent the face plate being positioned above the ends of the spring adjacent the end wall of the car.

In the drawings:

Figs. 1, 2 and 3 show the device applied to a car with an ordinary diaphragm face plate and with the springs rigidly secured to the car.

Figs. 4 and 5 show the device applied to a car with an apiced diaphragm face plate and with the springs rigidly secured to the face plate.

The diaphragm 2 is positioned between the face plate 3 and the end wall 4 of the car and the quarter elliptic springs 5 are interposed therebetween.

In Figs. 1 to 3, inclusive, the quarter elliptic springs are rigidly secured to the end wall of the car and movably secured to the diaphragm face plate, while in Figs. 4 and 5 the quarter elliptic springs are rigidly secured to the face plate and movably secured to the end wall of the car. Either construc-

tion, however, would come within the scope of this invention.

An apexed diaphragm 6 and apexed diaphragm face plate 7 is shown in Figs. 4 and 5, wherein the ends of the springs adjacent the face plate are above the ends of the springs adjacent the end wall of the car so that the latter ends may be mounted upon the end carline 8.

10 When the movable ends of the springs are adjacent the face plate a wearing plate 9 is used.

While I specifically describe one application of the device, it is understood that there 15 may be other forms and modifications thereof and I intend to file other applications for patents covering such other constructions.

I claim:—

20 1. In combination with the end wall and diaphragm face plate of a railway car; a pair of quarter elliptic springs, each spring having one end secured to one of the aforesaid elements, and means for attaching the 25 opposite ends of the springs to the other aforesaid element, which means permit the ends of the springs to move.

2. In combination with the end wall and diaphragm face plate of a railway car; a 30 pair of quarter elliptic springs, each spring having one end secured to the end wall of the car, and means for attaching the opposite ends of the springs to the face plate, which means permit the ends of the springs 35 to move.

3. In combination with the end wall and diaphragm face plate of a railway car; a

pair of quarter elliptic springs, each spring having one end secured to one of the aforesaid elements, and means for attaching the 40 opposite ends of the springs to the other aforesaid element, which means permit the ends of the springs to move a predetermined amount.

4. In combination with the end wall and diaphragm face plate of a railway car, a 45 pair of quarter elliptic springs, each spring having one end secured to the end wall of the car, and means for attaching the opposite ends of the springs to the face plate, 50 which means permit the ends of the springs to move a predetermined amount.

5. In combination with the end wall and diaphragm face plate of a railway car; a 55 pair of quarter elliptic springs, each spring having one end secured to one of the aforesaid elements, and means for attaching the opposite ends of the springs to the other aforesaid element, which means permit the ends of the springs to move, the ends of the 60 springs adjacent the face plate being above the ends of the springs adjacent the end wall of the car.

6. In combination with the end wall and diaphragm face plate of a railway car; a 65 pair of quarter elliptic springs, each spring having one end secured to the end wall of the car, and means for attaching the opposite ends of the springs to the face plate, 70 which means permit the ends of the springs to move, the ends of the springs adjacent the face plate being above the ends of the springs adjacent the end wall of the car.

GARTH G. GILPIN.
